CLAIM

The ornamental design for a contact lens, as shown and described.

DESCRIPTION

FIG. 1 is a rear perspective view of a contact lens showing our new design according to a first embodiment.

FIG. 2 is a front view of our new design shown in FIG. 1.

FIG. 3 is a rear view of our new design shown in FIG. 1.

FIG. 4 is a top view of our new design shown in FIG. 1.

FIG. 5 is a bottom view of our new design shown in FIG. 1.

FIG. 6 is a right-side view of our new design shown in FIG. 1.

FIG. 7 is a left-side view of our new design shown in FIG. 1; and,

FIG. 8 is a close-up view of a portion of our new design indicated by the box in FIG. 7.

The broken lines consisting of dot-dash lines are boundary lines that show that the claimed design extends to the boundary line but does not include the boundary line. The remaining portions of the contact lens rendered in short broken lines form no part of the claimed design.
